UNITED STATES PATENT OFFICE

93,905

DESIGN FOR A SHOE

Thomas R. Atkins, Clifftondale, Mass., assignor to Scholnick Shoe Co., Jamaica Plain, Mass., a corporation of Massachusetts

Application October 12, 1934, Serial No. 53,596

Term of patent 3½ years

To all whom it may concern:

Be it known that I, THOMAS R. ATKINS, a citizen of the United States, residing at Clifftondale, in the county of Essex and Commonwealth of Massachusetts, have invented a new, original, and ornamental Design for a Shoe, of which the following is a specification, reference being had to the accompanying drawing, forming a part thereof, in which

The figure is a view in perspective of a shoe showing my new design.

The opposite side of the shoe presents substantially the same appearance as that shown.

I claim:

The ornamental design for a shoe substantially as shown and described.

In testimony whereof, I have affixed my signature hereto.

THOMAS R. ATKINS.
